UNITED STATES PATENT OFFICE.

CHARLES D. McARTHUR, OF PITTSBURGH, PENNSYLVANIA, ASSIGNOR TO THE BLAW COLLAPSIBLE STEEL CENTERING COMPANY, OF PITTSBURGH, PENNSYLVANIA, A CORPORATION OF NEW JERSEY.

COLLAPSIBLE FORM.

1,168,659.

Specification of Letters Patent.

Patented Jan. 18, 1916.

Application filed November 3, 1910. Serial No. 590,566.

To all whom it may concern:

Be it known that I, CHARLES D. McARTHUR, a citizen of the United States, residing at Pittsburgh, in the county of Allegheny and State of Pennsylvania, have invented certain new and useful Improvements in Collapsible Forms, of which the following is a specification.

The invention relates to collapsible metal forms, and particularly to large size forms for the formation of subways and similar passages in which the walls are of concrete or other similar material. The invention has for its primary objects; the provision 10 of a form of large size which may be easily collapsed and moved from place to place; the provision of an improved arrangement whereby the sides of the form may be moved and positioned with respect to the wheels 15 upon which they are mounted; and the provision of an improved arrangement of supporting and collapsing means. One embodiment of the invention is illustrated in the accompanying drawings, wherein:—

25 Fig. 1 is a transverse section through a pair of forms in position in a pair of parallel subways of slightly different shape, the form in the right hand subway being in collapsed position, and the one in the left 30 hand subway being in expanded position, Figs. 2, 3 and 4 are enlarged detail views showing the method of mounting the wheels employed, Fig. 4 being a section on the line IV—IV of Fig. 3, and Fig. 5 is a longitudinal section through the form.

The invention is illustrated as applied to a subway form of large size and peculiar shape, but it will be understood that the more important features of invention are 40 regarded as applicable to a large variety of different shaped forms and to forms of small size as well as to those of large size. The two forms shown in Fig. 1 are identical with the exception that the lower portion 45 of the right hand wall of the right hand form is shortened by reason of the step or abutment at the lower portion of the wall, which abutment was required in this particular instance in order to provide room 50 for wires and cables at this point. The form is preferably used in lengths approximating 40 feet, and consists of sheet metal lagging plates 1, 1, 1, mounted upon channel beams 2, 2, 2, (Fig. 5) placed back to

back and secured detachably together by 55 means of bolts. The ribs for the upper or top portions of the form consist of angles 3, 3, 3, placed back to back instead of the channels. The top members of the form are adapted to swing downwardly as indicated at the right of Fig. 1, and when in upper position the inner edges of the top members are supported by means of the key member 5, which in turn is supported by means of struts 6 resting upon the tops of 60 the beams 7, which beams extend transversely of the form at each of the pairs of channels 2, 2. Pairs of brackets 4, 4 are secured to the flanges of the channels 2, 2, and slotted at 7', these slots receiving transverse pins 8 carried by the pairs of plates 9, 9, riveted to the ends of the beams 7, so that a sliding connection is provided 70 between the channels 2, 2 and the beams 7. The lower edges of the angles 3, 3 are secured pivotally to the channels 2, 2 by means of the plates 10 which plates also carry at 75 their lower ends the pivots 8. In order that the channels 2, 2 may be pulled inwardly 80 to the position indicated at the right of Fig. 1, when the top members of the form swing downwardly, the straps 11 are provided, which straps are pivoted at their outer ends to the channels 2, 2 and at their inner ends to the plates 10, 10. As the top members 85 swing down to the position indicated at the right of Fig. 1, the plates 11, 11 swing inwardly, pulling the straps 10, 10 inwardly, and with them the channels 2, 2, such inward movement of the channels 2, 2 with 90 respect to the beams being permitted by reason of the pin and slot connection 8, 7'.

In order to move the top portions of the form up and down, the pivoted struts 13 and 14 are provided, the mechanism for operating such struts being substantially the same on each side of the form. The cable 15 is secured to the upper portion of the strut 13 at the point 17, and extends around the pulley 18 on the beam 7, thence around an operating pulley 19 on the longitudinally extending shaft 20 (Fig. 5), thence around another pulley 21 upon the beam 7 and over a pulley 22 on the beam 7 to the lower end of the strut 13. An operating wheel 23 is 100 provided upon the shaft 20, and such wheel is rotated by means of the chain 24 extending 105 to the power mechanism 25 located upon

the side of the form. Any well known form of operating mechanism may be used at this point, the one employed being preferably of the type employing a worm as one of its gear elements, so that the chain 24 will be maintained in any position in which it is placed. The connections for operating the strut 14 on the opposite of the mold are substantially the same as those just described with the exception that the pulley corresponding to the pulley 21 is omitted.

Means whereby the form is supported and moved from place to place also constitutes a feature of my invention as indicated in Figs. 1 and 4. Angle irons 25' are mounted upon the corners of the abutments at the bottom of the subway, and these angles 25' serve as a support for the rails 26, the angles being supported in the subway at the left of Fig. 1 by means of the beams 27, 28 and 29, and in the subway at the right of Fig. 1 by the beams 30, 31 and 32. Upon these rails are mounted the wheels 33, which wheels are mounted upon the lower portions of the side members of the form in the manner indicated in detail in Figs. 2, 3 and 4, the purpose of the peculiar mounting shown being to provide for both the lateral and vertical movement of the sides of the form with respect to the wheels. A supporting framework upon the lower portion of the side member of the form is provided by the transverse angle 34 riveted to the ribs 2, 2, and by the vertical angles 35 riveted at their upper ends to the transverse angle 34, and at their bottom ends to a second transverse angle 36. The wheel 33 is carried in a movable cage consisting of the straps 37 and 38, the strap 37 being provided with the bolts 39 extending through slots 40, so that the cage may be adjusted vertically. When the bolts 39 are loosened the cage may be adjusted by means of the screws 41 mounted in the blocks 42. The strap 38 (Fig. 4) carries the bearings 43 and 44 in which the shaft 45 is mounted, the wheel 33 being freely slideable on such shaft or axle. A rod and turn-buckle connection 46 extending from one side of the form to the other may be employed for moving the side members in and out upon the wheels 33. The wheels are prevented from moving laterally upon the rails by reason of the double flange shown. It will be seen from the foregoing that the side portions of the form may be readily moved vertically to their proper position and also moved in and out to properly position the side sections and also to permit of the detachment of the lagging from the concrete.

The operation is as follows, assuming that the parts are in the position indicated in the right hand portion of Fig. 1. The wheels and the form carried thereby are moved along the track until the desired location is

reached. The screws 41 (Fig. 3) on both sides of the form, are then adjusted until the form reaches its proper vertical position. The power mechanisms 25 on each side of the form are then successively operated, thus 70 rotating the pulleys 23 and causing the struts 13 and 14 to assume the position indicated in the right hand portion of Fig. 1. The key member 5 and the strut 6 are then placed in position, locking the parts of the 75 form rigidly in the position shown at the left hand of Fig. 1. It will be seen that during the upward movement of the top members of the mold, the side members are moved laterally by reason of the connecting 80 straps 11 and the pin and slot connections between the brackets 4 and the plates 9 carried by the beams 7. After the concrete has set about the form the struts 6 and the key piece 5 are removed, and the operation of the 85 power means 25 causes the struts 13 and 14 to swing back to the position indicated at the right hand portion of Fig. 1, such movement of the struts and of the top portions 90 of the mold causing the side portions of the mold or form to move inward to the position indicated. The turn-buckle struts 47 and 48 (Fig. 1) are placed in position when the form is collapsed and serve to stiffen and brace the form while it is being moved to a 95 new location. The strut 49 serves as a means for moving the side member to which it is attached, in and out upon its wheels 33.

Having thus described my invention and illustrated its use, what I claim as new and desire to secure by Letters Patent is the following:—

1. In combination in a collapsible mold, a pair of parallel rails, a flanged wheel upon each rail, a side mold member upon each wheel mounted for movement in and out with respect to the wheel upon which it is mounted, and means for moving the members in and out, one side member and its wheel being independent of the other side member and wheel.

2. In combination in a collapsible mold; side members movable inwardly and outwardly; supporting wheels carried by the lower portions of the side members and with respect to which the side members are movable laterally; and means whereby the side members may be moved up and down with respect to the wheels.

3. In combination in a collapsible mold; side members movable inwardly and outwardly; and supporting wheels carried by the lower portions of the side members, and mounted upon such lower portions so that they the side members are movable laterally and vertically with respect thereto.

4. In combination in a collapsible mold; side members movable inwardly and outwardly; double flanged supporting wheels carried by the lower portions of the side

members; rails upon which the wheels are mounted; and means whereby the side members may be moved in and out with respect to the wheels and rails.

5 5. In combination in a collapsible mold; side members movable inwardly and outwardly; double flanged supporting wheels carried by the lower portions of the side members; rails upon which the wheels are 10 mounted; and means whereby the side members may be moved vertically and laterally with respect to the wheels and rails.

6. In combination in a mold of inverse U-shape; side members movable inwardly 15 and outwardly; a top member pivoted to the upper portion of each of the side members so as to swing inwardly and downwardly; a transverse member extending between the side members and carried thereby; and means 20 on the transverse member for supporting the opposing inner edges of the top members.

7. In combination in a collapsible mold; side members movable inwardly and outwardly; a top member pivoted to the upper 25 portion of each of the side members so as to swing inwardly and downwardly; means for swinging the top members; and means whereby the movement of the top members causes the side members to move in and out.

30 8. In combination in a mold of inverse U-shape; side members movable inwardly and outwardly; a top member pivoted to the upper portion of each of the side members so as to swing inwardly and downwardly; a 35 longitudinally extending key piece for holding the inner opposing edges of the top members when in upper position; a transverse member carried by the side members; and removable means carried by the transverse 40 member for supporting the key piece.

9. In combination in a collapsible mold; side members movable inwardly and outwardly; a top member pivoted to the upper portion of each of the side members so as 45 to swing inwardly and downwardly about its pivot; a transverse beam having sliding engagement with the upper portions of the side members and pivotal connection to the

lower edges of the top members; means for swinging the top members; and other connections between the side members and top members whereby the movement of the top members causes the side members to move in and out. 50

10. In combination in a mold of inverse U-shape; side members movable inwardly and outwardly; a top member having a side portion and an upper portion pivoted to the upper portions of each of the side members on the inside of such side member so as to 55 swing inwardly and downwardly; a transverse beam between and supported by the side members; and means on the beam for supporting the top members when in upper operative position. 60

11. In combination in a mold, a wheel, a side member mounted thereon for vertical and lateral movement with respect to the wheel. 65

12. The combination in a mold of inverse U-shape; a top member pivoted to the upper edge of each side member so as to swing inwardly and downwardly; a transverse beam carried by the side members; a downwardly projecting arm carried by each top member; 70 and operating means for each arm carried by the beam and engaging the lower portion of the arm for moving it upward. 75

13. The combination in a mold of inverse U-shape; a top member pivoted to the upper edge of each side member so as to swing inwardly and downwardly; a transverse beam carried by the side members; a downwardly projecting swinging arm carried by each top member; flexible means for each arm carried 80 by the beam and engaging the lower portion of the arm; and means for operating the flexible means to lift the arms and raise the top members. 85

In testimony whereof I have hereunto 90 signed my name in the presence of the two subscribed witnesses.

CHARLES D. MCARTHUR.
